UNITED STATES PATENT OFFICE

RALPH W. ANDERSON, OF WAUWATOSA, WISCONSIN

LOCOMOTIVE TENDER

Application filed May 25, 1931. Serial No. 539,672.

My invention relates to a tender provided with water holding and oil holding compartments intended for use with oil burning locomotives; that is to say, my invention relates to the provision of a structure whereby separate compartments for the water and the fuel oil are arranged without change in the usual exterior arrangement of the tender and therefore without material increase in cost over that of the usual coal holding type of tender at present in use.

The invention has for its object the provision of a rigid construction wherein the strains and pressures of the fluid contents and whereby undue surge of the oil will be prevented.

The objects and advantages of my invention will be readily comprehended from the detailed description of the accompanying drawings, wherein:

Figure 1 is a top plan view of my improved tender with portions broken away and shown in section, to disclose interior construction.

Figure 2 is a longitudinal sectional view taken substantially on the line 2—2 of Figure 1, as viewed by the arrows.

Figure 3 is a vertical sectional view taken on the line 3—3 of Figure 2, looking in the direction of the arrows.

Figure 4 is a detail sectional view of one of the discharge valved outlets, taken substantially on the line 4—4 of Figure 2.

My invention has for its object the conversion of the usual type of coal and water holding tenders into a water and an oil carrying tender of rigid construction, with the water holding compartment, indicated at 10 (see Figure 2) arranged in the usual manner in a locomotive tender and having the two side water legs 11, 11 extending from the compartment 10 along opposite sides of the tender toward the forward end of the tender in the usual manner and as more clearly seen in Figure 3.

The water holding main compartment 10 is provided with a sheet metal top wall 12 (see Figure 2) extending from side to side of the tender and secured to the tender side walls 13, 13, in water-tight relation therewith.

This top wall 12, which is disposed a pre-

determined distance beneath the top of the tender (as shown in Figure 2) at a point intermediate of the ends of the tender, is then bent downwardly, preferably in the sloping manner shown at 14, and at the intermediate portion thereof terminates in the vertical portion or partition wall 15 which is secured in water-tight relation with the bottom 16 of the tender.

The downwardly sloping partition portion 14 is diagonally formed or cut away at the opposite forward corners thereof, as shown in dotted lines, Figure 1, at 17, where it is united with the longitudinally disposed partition members 18, 18, at opposite sides of the tender and which slope downwardly toward each other, as shown in Figure 3, and terminate in the vertical portions 19, 19 which are in turn secured in fluid-tight relation with the bottom 16.

With the partitions arranged as just described, it will be seen that the main water holding chamber 10 is thus provided with two forwardly disposed water holding legs 11, 11 along opposite sides of the tender.

These partition portions 12, 14 and 18, 18, in turn, constitute the bottom walls of a part of the oil holding compartment 20; while the partition portions 15 and 19, 19 constitute side walls for the oil holding compartment.

As is apparent, the oil holding compartment 20 extends from side to side of the tender throughout the upper part thereof, namely above the partition 12 and the sloping partitions 18, 18, with the forward part 85 of the oil holding compartment, intermediate of the water-leg side walls 19, 19, namely along the longitudinal center of the tender, of greater depth, extending from top to bottom of the tender.

The rear end of the tender, at a distance forward of the rear end of the water chamber 10, is provided with a vertical partition 21 (see Figure 2) secured to the partition 12 and extending from side to side of the tender; and this vertical end wall 21 is secured to or formed integral with, the top wall 22. This top wall 22 extends from the rear wall 21 and from side to side of the tender, and unites with the front vertical wall 23 which extends 100

to the floor or bottom 16 somewhat rearward of the front end of the tender and therefore of the side water legs 11, 11; it being understood, of course, that these walls or partitions are either integral or secured together in fluid-tight relation and are also secured in fluid-tight relation with the main walls of the tender.

The sides, top and bottom walls of the compartments are reenforced by suitable metal brace members, which, in the particular exemplification, are shown preferably in the form of T-bars as shown at 23^a, extending transversely of the top and bottom partitions and vertically of the tender side walls at predetermined spaced intervals.

In order to prevent too great a surge of the oil during movement of the tender while a train is in operation, I provide a series of vertically disposed splash plates at 24, rigidly secured at top and bottom to the horizontally disposed brace bars 23^a. These splash plates 24 are shown preferably attached at top and bottom to the respective brace bars or T-irons 25 and thus constitute vertical braces between the top and bottom of the oil compartment, as shown in Figure 2; while the unattached ends of the splash plates are preferably bent at an angle to the main portion thereof, as shown at 25 in Figure 1, thus interrupting the surge or lash of the oil in directions both longitudinally and transversely of the tender. I prefer to arrange these splash plates in the staggered relation shown in Figure 1, 35 with each alternate splash plate arranged at the longitudinal center of the compartment while the intermediate plates are arranged on opposite sides of the longitudinal center and adjacent to the side walls of the tender; a pair of splash plates being shown intermediate of the central splash plates. The staggered arrangement of the splash plates permits flow of the oil; the plates at the same time forming brace members between the top 45 and the bottom walls throughout the oil compartment.

At the forward end of the tender where the oil compartment increases in depth, the splash plates 24 are likewise made of greater vertical dimensions as shown in Figure 2 and disposed intermediate of the top wall 22 and the downwardly inclined partitions 18.

While the splash plates, at the forward end of the tender intermediate of the water legs 11, 11 where the oil compartment is of greater depth, namely splash plates 24^a are provided with the large openings or manholes, as shown at 26 in Figure 2, to provide access to the various portions of the compartment. For the same reason, the splash plate adjacent to the sloping wall or partition 14 is also provided with a large opening or manhole at 27, which permits access to the upper rear end of the oil compartment for cleaning and other purposes.

In order to prevent a sidewise splash or surge of the oil in the deep forward end of the compartment, I provide a pair of longitudinally disposed splash plates 28, 28, arranged at a distance below the top 22 and above the bottom 16 of the compartment and extending from the front wall 23 back to the downwardly sloping partition or wall portion 14. The splash plates 28, 28 are intermediate of the median line and the side walls of the compartment; and in order to give sufficient rigidity to the lower longitudinal sides of the plates they are shown flanged as at 29 (Figure 3).

The various partition wall sheets are rigidly secured together in water-tight relation, preferably by suitable welding of the joints, as for example by intermittently welding the joints on one side and continuously welding them on the opposite side.

The top 22 of the tender, at the longitudinal center line thereof, and at the forward deep end of the oil compartment, is shown provided with a suitable manhole and cover at 30; the cover being secured in tight condition by suitable well-known clamps as at 31. This manhole also constitutes the filling hole for the oil compartment and therefore is provided with a suitable wire mesh screen or basket 32, to prevent ingress of extraneous matter.

The screen is removably held in place so as to permit ingress of a man through the manhole for purposes of cleaning and inspecting the interior of the oil compartment.

In order to permit entrance into the oil compartment, I provide a suitable ladder at 33, secured at its ends to the splash plate 24^a adjacent to the manhole 30 and which plate in turn has the large opening 26 therein, as shown in Figure 2. These openings 26 permit the oil compartment cleaner and inspector to have access to opposite ends of the deep portion of the compartment; while the manhole 27 enables him to enter the rear shallower portion of the compartment, and in order to enable the cleaner to reach the manhole 27 I provide the inner vertical wall or partition 15 with the grab-irons and stirrups 34, see Figures 2 and 3. The staggered arrangement of the splash plates 24 in the rear end of the oil compartment permit passage thereabout, thus enabling the entire oil compartment to be cleaned and inspected.

The oil compartment bottom at its forward deep end is provided with suitable valved outlets one of which is shown at 35 in Figure 2 and in enlarged section in Figure 4. These outlets are provided with a well known type of self closing conical valves 36 controlled by spring 37 held under tension by yoke 38 secured to the bottom 16 of the compartment. These valves are controlled by the pull chain 39 which extends through an opening in the top 22 of the compartment and is secured to

a well known type of control levers 40, which, in Figure 2, are shown in valve opening position and extend toward the forward end of the tender.

The forward deep end of the compartment is also provided with a suitable measuring stick 41; while the forward end wall is shown provided with a suitable ladder at 42.

I have shown and described what I believe to be a suitable embodiment of my invention, namely an embodiment which has been found in practice adapted to withstand the strains and stresses to which a tender of this character is subjected and at the same time a structure which may be readily incorporated in the type of water and coal holding tenders as at present employed, whereby an integral tender with water and oil holding compartments is provided without undue increase in expense of construction.

What I claim is:

1. In a locomotive tender, a rigid structure provided with a water compartment and an oil holding compartment, the water compartment extending from one end of the tender to an intermediate point and below the top of the tender and terminating in water-legs extending to the opposite end of the tender along opposite sides and below the top, while the oil compartment extends across the top of the water compartment and its water-legs and between said water-legs; said oil compartment being provided with a top rigidly secured to the sides of the tender and to the end walls of the oil compartment; the oil compartment at spaced points throughout its length being provided with vertically disposed splash-plates arranged to permit oil flow thereabout.

2. In a locomotive tender, a rigid structure formed to provide a water holding compartment and an oil holding compartment, both extending longitudinally of the tender with portions of one compartment arranged above portions of the other and a portion of the one compartment arranged between spaced portions of the other at the forward end of the tender; said compartments having tops, bottoms, sides and end walls all rigidly secured together in fluid-tight relation, with reenforcing bars extending transversely of the top walls and vertically on the side walls of the compartments; vertically extending splash-plates secured to the reenforcing bars and disposed transversely, said plates having angular disposed ends and certain of the plates arranged in off-set relation with each other and others are spaced from the side walls so as to permit passage thereabout, with certain of said plates provided with man-holes; and vertically extending splash-plates disposed in a lengthwise direction at one end of the oil-holding compartment in spaced relation with the top, bottom and side walls.

3. In a locomotive tender, a rigid structure formed to provide a water holding compartment and an oil holding compartment, with the oil holding compartment arranged above and between portions of the water holding compartment, both compartments extending to the forward end of the tender; said compartments having tops, bottoms, sides and end walls all secured together in fluid-tight relation; a series of vertically disposed splash plates secured at their upper and lower ends and extending transversely so as to permit passage thereabout, with certain of said plates being provided with man-holes; a vertically disposed ladder secured to one of said plates; hand and foot holds secured adjacent to another of said plates; and vertically disposed splash-plates extending in a lengthwise direction in spaced relation with the top, bottom and side walls.
